Fig. 2

Fig. 1

Fig. 3

Fig. 1 is a side elevational view of an electric fan, showing my new design, the opposite side being substantially a mirror image thereof;

Fig. 2 is a fragmentary top plan view, portions of the circular filter paper propeller discs being broken away for convenience in illustration; and

Fig. 3 is a bottom view thereof.

I claim:

The ornamental design for an electric fan, as shown and described.
